PROCESS FOR PREPARATION OF
ALPHA TOCOPHEROL

Frank J. Sevigne, Tarrytown, N.Y., assignor to Collett-
Week Corporation, Ossining, N.Y., a corporation of
New York
No Drawing. Filed Sept. 26, 1958, Ser. No. 763,450
6 Claims. (Cl. 260—345.5)

This invention relates to a process for the conversion 10 of tocopherol compounds from non-useful mixture to a biologically useful condition and, in particular, is concerned with the conversion of tocopherol isomers to a useful alpha form.

As is well known, alpha tocopherol has high vitamin 15 E activity, while non-alpha tocopherols, such as beta, gamma and delta, have much lower activity. Since the non-alpha forms predominate in nature many attempts have been made to convert them to the more biologically active alpha form. The non-alpha tocopherols differ from the alpha only in that one or both methyl groups are missing from the 5-7 positions. Attempts at conversion in the past have involved the direct methylation of the non-alpha tocopherols and have been reasonably successful.

Accordingly, this invention provides a method for the conversion of non-alpha tocopherol compounds to the alpha form, which is characterized by a sequence of steps comprising, first, oxidizing the compounds to quinone form and opening the chroman ring, thereupon halogenating the said compounds, in which step the quinone form is reduced, then reclosing the ring to give the desired tocopherol. The process is thus characterized by the sequence and combination of steps involved in the process, all of which are carried out under very mild conditions, which result in minimum formation of impurities and side reactions, the process being further characterized by the smoothness and ease with which it takes place in each step and the high yields obtained at each step in the operation.

The process of the present invention may be carried out with non-alpha tocopherols in various forms. It may be carried out with the various pure non-alpha tocopherols, i.e., β , γ , δ , or it may be carried out with impure mixtures of inert materials containing varying, even small, amounts of the tocopherols. For instance, it may be carried out with by products resulting from the refining of vegetable oils, for example, hot well sludge from the steam refining of vegetable oils, soybean oil, corn oil, wheat germ oil, peanut oil, olive oil and the like, are sources of the deodorizer sludge. Wheat carries variable but significant amounts of the tocopherol compounds. It will be understood that the several steps of the invention may be carried out in different ways with different raw materials and under modified conditions to suit the particular raw material being processed.

In summary, therefore, the process may be illustrated by the following sequence of reactions.

Summary of equations as follows:

2

40   Tocopherol occurs principally as α , γ , δ isomers in a large number of naturally occurring vegetable oils. Hence, a direct application of the process is in the conversion of γ , δ tocopherols to the biologically useful alpha form.

45   EXAMPLE I: CONVERSION OF β -TOCOPHEROL—
OXIDATION

One-tenth (0.1) part of pure beta-tocopherol was dissolved in 5 parts of anhydrous methyl alcohol. A solution containing 0.25 parts of $\text{FeCl}_3 \cdot 6\text{H}_2\text{O}$ in 5 parts of methyl alcohol was added dropwise over a period of fifteen minutes. Twenty (20) parts of distilled water were added and the mixture was extracted with 20, 10 and 10 part portions of ethyl ether. The combined ether solutions were washed five times with 10 part portions of distilled water, dried with anhydrous sodium sulfate, filtered, and the solvent distilled off under vacuum.

The reddish-yellow oil obtained was subjected to a second oxidation under identical conditions. The oil was dissolved in 5 parts of anhydrous methyl alcohol, a solution of FeCl_3 (0.25 part $\text{FeCl}_3 \cdot 6\text{H}_2\text{O}$ in 5 parts CH_3OH) was added dropwise over a fifteen-minute period. Twenty (20) parts of distilled water were added and the mixture was extracted with 20, 10 and 10 part portions of ethyl ether. The combined ethyl ether extracted was washed five times with 10 part portions of distilled water, dried over Na_2SO_4 , filtered and the solvent removed under vacuum. The residue consisted of a red-yellow oil.

For the oxidation phase of the process an oxidation system or agent having about the oxidation potential of the ferric chloride solutions is desired. It is essential in the process to oxidize to the quinone form and to leave

the chroman ring, but without causing degradation of the intermediate benzoquinone.

The following typical data summarize the course of the oxidation reaction carried out at room temperature:

(1) *Oxidation at room temperature*

FeCl₃-conc.=1 molar

Time, min.:	E _{1 cm.} percent
0	
30	314
60	321
120	339
240	321
360	255

$\lambda=261$ millimicrons.

E=Extinction coefficient U.V.

The only significance of the data is that the measurement may be used as a control and reaction time should be adjusted to maximize it. The data listed above was obtained with γ tocopherol but apply also to β , with minor variations.

(2) *Chloromethylation and reduction*

Eight hundredths part of the oxidation product was dissolved in 4 parts of ethyl ether. Two tenths (0.2) part of concentrated hydrochloric acid and 0.1 part of formaldehyde was added and the mixture stirred under nitrogen for three hours. Two tenths (0.2) part of concentrated hydrochloric acid was added and then 0.25 part of zinc dust was slowly added over a thirty-minute period. The mixture was then stirred for an additional two-hour period. The mixture was then extracted three times with 10 part portions of ethyl ether. The ether extracts were combined, washed six times with 5 part portions of distilled water, dried over Na₂SO₄, filtered, and the solvent removed under vacuum.

(3) *Cyclization*

Six hundredths part of the reduced chloromethylated product was dissolved in 5 parts of glacial acetic acid. Five tenths (0.5) part of hydrobromic acid and 0.2 part of zinc dust were added and the mixture refluxed for ten minutes under nitrogen. After diluting with 40 parts of distilled water, the acid solution was extracted three times with 30 part portions of ethyl ether. The combined ether extracts were washed twice with 10 part portions of 2N Na₂CO₃ solution and then six times with 10 part portions of distilled water. The ether solution was dried over Na₂SO₄, filtered and the solvent removed under vacuum. The residue consisted of a pale yellow oil containing 72 percent total tocopherol according to assay. The alpha tocopherol content of the oil was 53 percent as indicated by chemical assay according to the method of Quaife (J. Biol. Chem., 175, 605, 1948).

EXAMPLE II: CONVERSION OF δ -TICOPHEROL

(1) *Oxidation*

One-tenth (0.1) part of pure δ -tocopherol was dissolved in 5 parts methyl alcohol and twice oxidized with a 10 mole FeCl₃-methyl alcohol solution during consecutive periods of ten minutes in the manner of Example I. The residue obtained was a yellow-red oil of δ -tocopheryl quinone.

(2) *Chloromethylation*

The quinone was dissolved in 5 parts of ether and vigorously stirred with 0.5 part concentrated hydrochloric acid and 0.2 part of formaldehyde for two hours under nitrogen.

(3) *Reduction*

For the reduction 0.2 part concentrated hydrochloric acid was added and then 0.5 part Zn-dust with stirring over a ten-minute period. The reaction was continued for two hours; 5 parts ether were added and the ether

layer decanted from the acid solution and the Zn residue. The ether solution was washed ten times with 5 part portions of water, dried over Na₂SO₄, filtered and evaporated under vacuum. The product obtained was a pale yellow oil.

(4) *Cyclization*

0.090 part hydroquinone was dissolved in 2 parts dioxane and refluxed for 5½ hours under N₂ with 0.2 part stannous chloride and 0.15 part concentrated hydrochloric acid. The light reddish solution was diluted with 10 parts water and extracted three times with 10 parts ether. The ether solutions were washed six times with 10 parts of water, dried over Na₂SO₄, filtered and the solvent evaporated under vacuum. The residue obtained was a yellow oil.

EXAMPLE III: METHYLATION OF GAMMA-TOCOPHEROL

(1) *Oxidation*

One and eleven hundredths (1.011) parts gamma-tocopherol were dissolved in 23 parts ethyl alcohol with a solution of 2.5 grams FeCl₃·6H₂O in 20 parts ethyl alcohol added, with stirring, for ten minutes. Then the reaction was continued with refluxing for five minutes. The colorless solution quickly became red. After cooling, 150 parts of water were added and the oxidized organic part was extracted with 60, 40 and 40 parts ethyl ether. The combined ethyl ether solutions were washed five times with 60 parts water, dried over Na₂SO₄ and the solvent distilled off under vacuum. The residue obtained was a red oil 1.017 parts.

(2) *Chloromethylation*

One (1.00) part quinone was dissolved in 20 parts ether and vigorously stirred under nitrogen with 2 parts concentrated hydrochloric acid and 1 part of formaldehyde for one hour. After a further addition of 0.3 part of formaldehyde the reaction was continued for two hours. During the reaction time the color turned from red to yellow-red.

(3) *Reduction*

To the solution thus obtained were added 2 parts concentrated hydrochloric acid and then during 25 minutes, 2.5 parts zinc-dust. The reduction was stopped after 2½ hours. The red color changed to colorless within five minutes. Thirty (30) parts of ether were added, shaken well and then decanted from the acid solution. This was repeated twice. The combined ether solutions were washed eight times with 30 parts of water, dried over Na₂SO₄, filtered, and evaporated under vacuum. The residue obtained was a pale yellow oil, 0.933 part (yield 90 percent).

(4) *Cyclization*

0.920 part of the above hydroquinone was dissolved in 10 parts dioxane. One (1) gram SnCl₂ and 0.7 part concentrated hydrochloric acid were added and the mixture was heated at reflux for six hours. The color turned yellow-red. After adding 30 parts of water, this solution was extracted three times with 30 parts ether. The organic phase was washed six times with 40 parts water, then dried over Na₂SO₄, filtered, and stored overnight in an icebox. After evaporation under vacuum a light, yellowish oil remained, 1.12 parts (yield 92 percent).

EXAMPLE IV: CONVERSION OF SOYBEAN OIL SLUDGE

Raw material obtained from soybean oil sludge produced in the steam treatment of soybean oil was used in the process, as described in Examples I-III. It contained a random mixture of α , γ , δ tocopherols in total concentration of 5 percent. The sludge was saponified with alcoholic potassium hydroxide, and the unsaponifiable fraction was extracted with petroleum ether and the ether distilled off. This was then dissolved in methyl alcohol

and frozen to separate the sterols to give a tocopherol concentrate having the following characteristics:

	Percent
Alpha Tocopherol	4.0
Non-alpha Tocopherol	36.5

(1) *Oxidation with FeCl₃ to tocopheryl quinone*

To 50 parts of the thus obtained oil dissolved in 350 parts of warm absolute methanol, there was added, with stirring, 25 parts of FeCl₃.6H₂O dissolved in 150 parts of absolute methanol. The dark reddish-green solution was transferred to a separatory funnel, diluted with 2500 parts of water, and extracted three times with 300 part portions of petroleum ether.

(2) *Chloromethylation*

The petroleum ether solution was concentrated in vacuo to about 250 parts; 50 parts of concentrated hydrochloric acid and 25 parts of formaldehyde were added and the mixture stirred for three hours under nitrogen.

(3) *Reduction with Zn dust and concentrated HCl*

To the above mixture were added with stirring, 50 parts of concentrated hydrochloric acid and 50 parts of Zn dust, the latter being added in small increments over a period of two hours. The petroleum ether layer was separated, washed five times with equal portions of water, dried with anhydrous sodium sulfate, filtered, and the solvent removed under vacuum on a steam bath. The residue consisted of a light orange oil (45.1) grams.

(4) *Ring closure with acetic acid, ZnCl₂ and Zn dust*

To the light orange oil, 45.1 parts was added a mixture of 200 parts 80 percent acetic acid, 20 parts of ZnCl₂ and 2 parts of zinc dust. The solution was heated to 60° C., and maintained at that temperature for six hours with constant stirring. The mixture was cooled to room temperature, transferred to a separatory funnel, diluted with water (2,000 parts) and extracted three times with 300 part portions of petroleum ether. The petroleum ether layer was separated, washed eight times with 100 part portions of water and dried with sodium sulfate. The filtered petroleum ether solution was evaporated to dryness in vacuo on a steam bath. The residue consisted of a yellow oil (40.2 grams), having the following analysis:

	Total Tocopherol	α	Non α
Methylated material, percent	33.0	27.4	5.6

In typical routine plant operation, yields are easily obtained as follows:

(1) Oxidation	95.5 percent.
(2) Chloromethylation	Quantitative 90 per-
(3) Reduction	cent overall.
(4) Cyclization	92 percent.

The examples have been stated in quite specific terms as detailed instructions for the preparation of the alpha tocopherol. This is because they represent actual plant practice and as such a useful approximation of ideal quantitative conditions. It is to be understood, of course, that in any one of the examples, the solvents used, precise temperature levels and extracting materials used may be varied without materially departing from the sequence of operations in the process. When no temperature is specified, the reaction was conducted at ambient temperature.

For example, in the conversion of the tocopherol compound in the initial oxidation step in any one of the Examples 1, 2 and 3, the solvent may be ethyl, propyl, or butyl alcohol. It is merely necessary that it be sufficiently indifferent to the oxidation conditions to be unaffected

in the reaction. Similarly, in place of preferred ferric chloride solution, a gold chloride or other metal salt oxidizing agent having about that oxidation potential will be useful. Since the purpose of the oxidation step is merely to open the chroman ring, the conditions of reaction should be directed to that result.

In the extraction of the reaction product, ethyl ether is used, because that has the advantage of being a good solvent immiscible with water and effective for the purpose. However, other ethers, such as methylethyl ether may be used, because the basic requirement is high solvent capacity for the tocopherol quinone.

In the chloromethylation and reduction phase of the operation, the solvent used was ethyl ether in the several examples, but it is to be understood, of course, that any solvent for the reactants would be useful. Here methyl ether or methylethyl ether will serve the purpose. In the actual chloromethylation which is conducted, the formaldehyde and hydrogen chloride may be used in the gaseous form, or the formaldehyde may be used in the solid paraaldehyde form. Similarly, the reducing agent is zinc dust and hydrochloric acid because it is a convenient one, but actually any pair of reactants, for example, a zinc amalgam is suitable for forming the nascent hydrogen.

In the cyclization step of reaction, glacial acid hydrochloric acid and zinc dust were used. The reactions were specific but it is to be understood that any reactants usable for the purpose of closing the chroman ring might be used.

Although the invention has been described with reference to a limited number of examples, it is to be understood variations thereof may be practiced without departing from the spirit or scope of the invention.

What is claimed is:

1. The process of converting a tocopherol selected from the group consisting of beta, gamma, and delta tocopherol and mixtures thereof to the alpha tocopherol form, comprising, oxidizing a material containing said tocopherol under mild oxidizing conditions whereby the chroman ring opens forming a tocopheryl para quinone, chloromethylating said para quinone with formaldehyde and hydrogen chloride at about ambient temperature, whereby any hydrogen atoms present on the phenyl ring are replaced with chloromethyl radicals, reducing said compound with zinc and hydrochloric acid whereby the chloromethyl radicals are converted to methyl radicals, acidifying the mixture and thereby closing the ring of said compound whereby alpha tocopherol is produced from said tocopheryl quinones.

2. The process of claim 1 wherein the oxidation step is conducted by reacting the tocopherol with ferric chloride.

3. The process of claim 1 wherein the chloromethylation step is conducted by reacting the quinone with a formaldehyde yielding material and hydrochloric acid.

4. The process of claim 1 wherein the reduction step is conducted by reacting the chloromethylated product with zinc dust and hydrochloric acid.

5. The process of claim 1 wherein the cyclization step is conducted with stannous chloride.

6. The process of claim 1 wherein the cyclization step is conducted with zinc chloride.
